UNITED STATES PATENT OFFICE.

ARTHUR DICKERSON, OF SALT LAKE CITY, UTAH, ASSIGNOR TO DICKERSON CARBURETOR COMPANY, A CORPORATION OF UTAH.

CARBURETOR.

Application filed January 6, 1925. Serial No. 895.

My invention relates to carburetors for internal combustion engines, and has for its object to provide a new and improved carburetor whereby a limited amount of carburetted gas may be supplied to the engine, and automatically increased in volume.

These objects I accomplish with the device illustrated in the accompanying drawings in which similar letters and numerals of reference indicate like parts throughout the several views, and as described in the specification forming a part of this application and pointed out in the appended claims.

In the drawings in which I have shown the best manner of applying the principles of my invention, Figure 1 is a side elevation of the device. Figure 2 is a vertical section on line 2—2 of Figure 3. Figure 3 is a plan view of the device. Figure 4 is a plan view of the closure plate of the float chamber and the valve support. Figure 5 is a horizontal cross-section of the device, on line 5—5 of Figure 2.

My invention consists of a fuel chamber casing A, having a closure plate B secured thereon by the tap screws 1. On the top of said closure plate B is secured a casing R part of which forms the mixing chamber D which is secured to the intake manifold of the engine. The interior of said casing A is hollowed out as a float chamber C with a wing recess 2 opening to said chamber C. Within said chamber C and recess 2 is eccentrically pivoted the counter weighted displacement member E which takes the place of the commonly used float, and is raised or lowered by the amount of gasoline in the said chamber C. A priming bowl F is centrally formed on the said closure plate B, and concentrically in said bowl F the valve casing G is vertically secured, and which is connected with the interior of said float chamber C by the port 3, through which the fuel, such as gasoline, is introduced into the priming bowl and mixing chamber. The fuel supply pipe 4 is screwed into the upper face of said closure plate B with its end formed into a valve seat, in which the needle valve 5 is seated, which valve regulates the flow of gasoline as it is raised or lowered by said displacement member E. In the lower portion of said valve casing G is provided a priming port 6, through which the gasoline is supplied for priming the device and when idling the engine. A valve stem H is screwed

into the upper portion of said casing G, with its medial portions spaced from the interior of said casing, and its lower end closely fitted within said casing to close said port 6 when the stem is moved longitudinally. In the side wall of said casing G are also provided spaced apart exit ports 7, through which the gasoline passes into the mixing chamber D. An air inlet 8 is bored through the upper portion of said valve stem H and a fuel port 9 is provided through its lower end portion to allow gasoline to pass to said exit ports 7. When the valve stem is inserted in the casing G a fuel well 6^a is formed in the bottom of the said casing G and the amount of fuel therein is regulated by the amount of fuel in the float chamber A as it is directly connected therewith by the port 3. Within the interior of said mixing chamber D is provided an eccentrically mounted butterfly choke valve 10, and the throttle valve 11, and more centrally in said chamber D I provide a constricted throat in which I provide two flap valves 12, of different weights, which regulate the flow of the main air supply to the mixing side of the device, as they are operated by the suction of the engine. The said choke valve 10 is eccentrically mounted on the shaft 10^a, which is pivoted in the walls of the casing D and a lever arm 10^b is secured to the free end of the said shaft. The said flap valves 12 are preferably of the same superficial area, but, by making one of them thicker, or of heavier metal, the lighter of the two will be moved first, as when the air current is not so strong, and when, by driving the engine faster, the air current becomes stronger the heavier of the said valves 12 will be moved on their common pivot and air will pass both valves. I use said valves to overcome the pulsative movements of the choke valves. The said valves seat in a restricted throat or narrow place provided in the said mixing chamber D. The said choke valve 10 may be manually operated as hereafter described, or it may be operated by the suction of the engine pistons, and said choke valve is not connected with said flap valves 12, but moves independently of them. A needle valve 13 is provided in the upper end of the said valve stem H, by which air is allowed to enter said casing G to prevent excess vacuum action on the supply of gasoline in said casing. A lever 14 of the bell crank type is secured on 110

the upper end of said valve stem H, by which the said stem is partially rotated and moved longitudinally when said lever is operated. The said lever 14 is also connected 5 with said choke valve 10 by the compensating spring 16. A jam nut 15 is screwed on the upper end portion of said casing G to fasten the mixing chamber D to the said closure plate B and float casing A. The compensating spring 16 is secured at one end to 10 said bell crank lever 14 and at its other end to said choke valve lever arm 10^b to allow movement of said choke valve independently of the lever 14, when actuated by the suction 15 of air through the mixing chamber D. When the choke lever 14 is moved clockwise the port 6 is opened and when the said lever is rotated counter clockwise the said port 6 is closed. When the said lever 14 is moved 20 the spring 16 pulls the lever arm 10^b and opens the butterfly valve 10 accordingly and the said butterfly valve 10 is closed when the lever 14 is turned counter clockwise. When the choke valve 10 and valve stem H are 25 manually operated, by throwing said lever 14 in a clockwise direction, the valve 10 will be opened, and the valve stem H will be moved upwardly, whereby the port 6 is partially opened and fuel is allowed to flow into the priming bowl F and drawn through the 30 port 18 into the mixing chamber D by the suction of the engine. When the valve stem H is rotated a full turn the port 6 is fully opened and as all of the ports 7 are always 35 open gasoline will pass through them into the mixing chamber D with the required amount of air as passed by the choke valve 10 due to the suction of the engine. With the engine running the required amount of 40 air will be drawn at all times past the choke valve 10, the flap valves 12, and mixed with the gasoline. The said spring 16 normally holds the said choke valve 10 closed, and acts against the movement of said lever 14. 45 An air port 17 is provided in said closure plate B, through which air is drawn into said priming bowl F, and another port 18 is provided in said closure plate B through which a mixture of air and gasoline is drawn 50 into the mixing chamber D. The said port 18 is larger than the port 17 to create a tendency of vacuum in the priming bowl F. When the engine is idling the flap valves 12 will be closed, and only the air passing

through said ports 17 and 18 enters the engine with the required amount of gasoline which passes through port 6. 55

Having thus described my invention I desire to secure by Letters Patent and claim:—

1. A carburetor comprising a float chamber, a cover plate therefor having two air ports therein of different sizes; a mixing bowl provided in said plate below said air ports; a feed conduit connecting said float chamber and the interior of said mixing bowl; a valve casing secured in the bottom of said mixing bowl, having an exit port near the bottom of said mixing bowl, and other spaced apart exit ports in its side wall; a valve stem operable in said valve casing to open and close the first mentioned exit port, and having its medial portion spaced from said valve casing to form a passage therewith; an air conduit opening into the upper end of the said passage, and a fuel conduit 70 opening into its lower end to allow passage of fuel therethrough and means to control the amount of fuel drawn up through said exit ports commensurate with the speed of the engine. 80

2. A carburetor comprising a float chamber; a closure plate therefor; a mixing bowl formed in the upper face of the closure plate and depending into said float chamber; a casing secured on said plate, having a mixing chamber formed therein, which chamber has a restricted throat therein; pivoted flap valves normally closing said constricted throat and operable by the suction of the engine pistons; a valve casing secured in the bottom of said mixing bowl and extending upwardly through said mixing chamber and having exit ports in its side walls opening into the said casing and one of which opens into the interior of said mixing bowl; a valve stem operable in said valve casing and adapted to open and close said last mentioned port; a bell crank lever to operate said stem; a choke valve eccentrically mounted in said mixing chamber and a compensating spring connecting said lever and choke valve to allow said choke valve to operate independently of said bell crank lever when acted upon by suction. 95

In testimony whereof I have affixed my 105 signature.

ARTHUR DICKERSON.
